UNITED STATES PATENT OFFICE.

BENJAMIN T. BABBITT, OF NEW-YORK, N. Y.

AUTOMATIC BOILER-FEEDER.

SPECIFICATION forming part of Letters Patent No. 244,518, dated July 19, 1881.

Application filed May 20, 1881. (No model.)

To all whom it may concern:

Be it known that I, BENJAMIN T. BABBITT, of the city and county of New York, in the State of New York, have invented a certain 5 new and useful Improvement in Automatic Boiler-Feeders, of which the following is a specification.

The invention consists in a novel combination, with a boiler, of two water-chambers, into 10 one of which water is delivered by gravity from any convenient source of supply, and from which the water is forced by pressure of steam from the boiler into the second chamber, from whence it passes to the boiler, the several 15 pipes connecting the water-chambers with the boiler and with each other being provided with cocks or valves, which are operated by a weighted beam or lever controlled by floats within the two water-chambers, as fully hereinafter described.

The accompanying drawing represents a portion 20 of a boiler and a water-tank and a partly-sectional elevation of an apparatus embodying my invention for feeding the boiler.

A represents a steam-boiler, which may be 25 of any ordinary or other type, and of which no description is necessary, and B designates a water-tank, which may be supplied from any elevated source of supply or from hydrant-pressure in places provided with water-works.

C D designate two water-chambers, through 30 which the water passes from the tank B to the boiler A, the former water-chamber C being sufficiently below the water-tank to permit water to run into it therefrom, and the latter water-chamber D being elevated above the boiler, so that water will run into the boiler therefrom by gravity. In the water-chambers C D are arranged floats C' D', and connected 35 with said floats are rods C² D² extending upward through stuffing-boxes S in the tops of the water-chambers.

E designates a lever or beam, pivoted at a to the standard or upright F and provided 40 with an upwardly-projecting arm, E', which is weighted at b, so that whenever said lever or beam is shifted slightly beyond a central position by either of the floats C' D' its movement will be completed by reason of the weight, 45 which is shifted by the movement of the lever from one side to the other of the center by the

positive movement imparted to the lever or beam by the floats C' D'.

G designates a pipe leading from the water-tank B to the water-chamber C, and provided 55 with a cock or valve, G', whereby the passage of water through it is controlled.

H designates a pipe leading from the lower part of the water-chamber C to the water-chamber D, and provided with a cock or valve, H', 60 whereby the passage of water through it is controlled.

I designates a pipe leading from the lower part of the water-chamber D to the boiler, for delivering water from said chamber into the 65 boiler, and provided with a cock, I', for controlling the passage of water through it.

J designates a steam-pipe leading from the boiler above the water-line to the upper part of the water-chamber C; and K designates a 70 branch steam-pipe leading from the pipe J and serving to conduct steam from the boiler to the water-chamber D. The passage of steam through the pipes J K is controlled by cocks or valves J' K', as clearly shown.

The cocks or valves G' J' in the pipes G and 75 J are operated by a rod, L, which receives motion from the lever or beam E. The cocks or valves H' I' in the pipes H I are operated by a rod, M, from the lever or beam and the cock or valve K' in the pipe K is operated by a rod, N, connected with the rod M.

As clearly shown, the lever or beam E engages with elongated openings or slots c in the rods L M, thereby enabling the several cocks 85 or valves to be operated during the first movement of the lever or beam E, and permitting the said lever or beam to complete its final movement without operating said cocks or valves.

I will now describe the mode of operation of my improved apparatus.

In the drawing the water-chamber C is represented as full of water, and during the time of filling said chamber of course the cock G' 95 in the pipe G must be open to permit the passage of water from the tank B to the water-chamber C, and at the same time the cock J' in the pipe J must have been closed to shut off the steam-pressure from the said water-chamber. By the filling of the chamber C the float C' contained therein is raised, and acting upon 100

the lever or beam E tilts the same into the position shown in full outline in the drawing. This tilting of the lever or beam E shuts the cock G', thus closing communication between it and the water-tank, and at the same time opens the cock J' to admit steam to the chamber C above the water, and also the cock H' to permit the water in the chamber C to be forced into the chamber D by the pressure of steam 15 from the boiler. During this operation it will be observed that the cocks I' K' are closed, thus cutting off all communication between the boiler and the chamber D. As the water is forced into the chamber D the float D' therein rises, and as soon as it rises sufficiently to throw or tilt the lever or beam E beyond its center of gravity the latter falls, opening the cock G to permit water to pass from the tank B into the water-chamber C, closing the cocks H' J' 20 to cut off all communication between the chamber C and the chamber D and boiler, and opening the cocks I' K' to establish an equilibrium of pressure in the chamber D, and in the boiler to permit water from said chamber to flow into

the boiler. As the water enters the chamber 25 C the float C' rises until the lever or beam E is tilted, when the operation is completed.

By my invention I provide a simple and reliable apparatus applicable for feeding steam-boilers automatically, and thus dispensing with a direct-acting or other pump usually employed for such purpose, and effecting the saving of the steam commonly employed for driving such a pump.

What I claim as my invention, and desire to secure by Letters Patent, is—

The combination, with the boiler, the feed-water tank, and the two water-chambers and floats, of the several pipes and valves G G', H H', I I', J J', K K', arranged substantially as described, and the weighted lever or beam and connections adapted to be operated by said floats to simultaneously shift all said valves.

B. T. BABBITT.
